UNITED STATES PATENT OFFICE.

FRANK T. RADECKE, OF WAUKEGAN, ILLINOIS.

DESIGN FOR A PUMP-CASING.

SPECIFICATION forming part of Design No. 31,533, dated September 19, 1899.

Application filed August 14, 1899. Serial No. 727,216. Term of patent 14 years.

To all whom it may concern:

Be it known that I, FRANK T. RADECKE, a citizen of the United States of America, and a resident of Waukegan, in the county of Lake and State of Illinois, have invented a new and original Design for Pump-Casings, of which the following is a specification, reference being had to the accompanying drawings, forming a part thereof.

10 Figure 1 is a perspective view of a pump-casing made according to my new design. Fig. 2 is a top plan of same. Fig. 3 is a bottom plan of same.

15 The leading or material feature of my design consists in the pump-casing in the form of a cylinder reduced or flattened on one side, having a shaft projecting from said flattened part, having its periphery on the opposite side of uniform diameter from a transverse 20 plane above said reduced part to a transverse plane below same, and a spout projecting from said periphery.

25 The cylinder or pump-casing 1 forms a complete cylinder at the top, has the flattened surface 2 on one side and the cut or opening

3 above said flat surface communicating with the interior or chamber 4. The shaft 5, projecting from said flat surface, is reduced at its free end 6 and has the enlargement or shoulder 7 at its base. The spout 8, projecting from the cylinder opposite said reduced part, is provided with a depending nozzle 9 and a flange 10.

The cylinder 1 has a flange 11 at its top, is reduced at the bottom to form the depending 35 flange 12, and has a slight enlargement 13 below the flattened part 2. 14 represents lugs projecting into the interior of the chamber 4.

What I claim as new, and desire to secure 40 by Letters Patent, is—

The design for a pump-casing, substantially as herein shown and described.

Signed by me at Chicago, Illinois, this 11th day of August, 1899.

FRANK T. RADECKE.
